EXHAUST PIPE AND BOILER TUBE
COLLAPSER AND PULLER

Otto Kouba, North Bergen, N. J.

Application February 15, 1940, Serial No. 319,069

6 Claims. (Cl. 294—103)

This invention relates to new and useful improvements in an exhaust pipe and boiler tube collapser and puller.

More specifically, the invention proposes the construction of a device for aiding in removing the exhaust pipes of automobiles and boiler tubes, characterized by a bar adapted to be positioned in a substantially horizontal position and having a gripper member for encircling the pipe or tube to hold the bar in position thereon, and for permitting the front of the bar to be moved downwards to collapse the top wall of the pipe or tube to permit the device to obtain a grip thereon.

Still further it is proposed that the bar be extended in an aligned position with the axis of the pipe or tube in the collapsed position thereof for permitting the bar to be pulled outwards for disengaging the pipe or tube from the respective object to which it is attached.

Still further it is proposed to characterize the gripper member by a chain having one of its ends securely attached to said bar and the other of its ends removably attached thereto in a manner to permit the same to be conveniently attached to the end of the boiler tube or exhaust pipe.

Still further it is proposed to provide the bar with a plurality of tip portions to provide a longer length about which the bar may be pivoted, and which are adapted to be removed to shorten the length of the bar to permit the same to be more conveniently used in a limited amount of space.

Still further it is proposed to provide a means for adjustably mounting the gripper member in various positions along the end portion of the bar to permit the gripper element to be adjusted to meet the particular requirements of the job at hand.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of an exhaust pipe and boiler tube collapser and puller constructed according to this invention.

Fig. 2 is a plan view of Fig. 1 showing the collapser and puller upon the end of a portion of pipe.

Fig. 3 is an end elevational view looking in the direction of the line 3—3 of Fig. 2.

Fig. 4 is a side elevational view looking in the direction of the line 4—4 of Fig. 2.

Fig. 5 is an elevational view of an exhaust pipe and boiler tube collapser and puller constructed in accordance with this invention.

Fig. 6 is a sectional view on the line 6—6 of Fig. 5.

Fig. 7 is an enlarged detailed view of a portion of a collapser and puller constructed according to a still further modification of the invention.

Fig. 8 is a sectional view on the line 8—8 of Fig. 7.

Fig. 9 is a view similar to Fig. 7 but illustrating a further modification of the invention.

Fig. 10 is a view looking in the direction of the line 10—10 of Fig. 9.

Fig. 11 is an elevational view of a collapser and puller constructed according to a still further modification.

Fig. 12 is a view looking in the direction of the line 12—12 of Fig. 11.

The exhaust pipe and boiler tube collapser and puller, according to this invention, includes a bar 10 which is adapted to be positioned in a substantially horizontal position upon the end of an exhaust pipe or boiler tube 11. The bar 10 is preferably constructed of metal and is provided with an upturned front end portion 10^a about which the bar is adapted to be pivoted to assume a position parallel with the axis of the pipe or tube 11 as shown in Fig. 4.

A gripper member is mounted on the bar 10 adjacent the upturned front end 10^a and is adapted to encircle the pipe or tube 11. This gripper element comprises a double headed bolt 12 having its intermediate portion securely cemented to the bar 10 intermediate of its ends. A length of chain 13 is provided at one end with a ring 13^a securely mounted on the bolt 12 or one side of the bar 10. The other end of the chain 13 is provided with a hook 13^b which is adapted to be engaged upon the bolt 12 on the other side of the bar 10.

The operation of this form of the invention is as follows:

For removing the exhaust pipe of an automobile or a boiler tube the upturned end 10^a is rested on the tip of the pipe or tube 11 in a substantially horizontal position. The hook 13^b is removed from the bolt 12 so that the chain 13 may be engaged across the bottom of the tube 11 and upwards along the side thereof

to be reengaged upon the bolt 12 as shown in Figs. 2 to 4. A bar 10 is then pivoted downwards to assume a position parallel to the axis of the pipe or tube 11 causing the top wall thereof to be collapsed as shown in Figs. 3 and 4 so that the gripper member will take a secure hold of the end of the pipe or tube 11 so that when the bar 10 is pulled outwards the pipe or tube will move therewith and be disengaged from the respective object to which it is attached.

According to the modification of the invention shown in Figs. 5 and 6 the ring 13^a of the chain 13' is passed through a bolt 14 which is in turn passed through an opening 10^b formed in the bar 10 adjacent the turned end 10^a thereof. A flange 14^a is formed on the bolt 14 adjacent the end through which the ring 13^a passes and is adapted to contact one face of the bar 10. The other end of the bolt 14 carries a nut 15 which is adapted to be clamped against the face of the bar 10 for connecting the end of the chain 13 to the bar and for permitting the chain 13' to be removed therefrom when desired. The free end of the chain 13' carries a hook 13^b which is adapted to be engaged with the ring 13^a of the chain 13' after being passed around the pipe or tube 11 for holding the chain in position thereon.

The upturned end 10^a of the bar 10 is provided with a plurality of removable tip portions 10^{aa} each of which is provided with a reduced shoulder portion 16 provided with threads and which is adapted to be threadedly engaged into a receiving socket 17 formed in the adjacent end of its next adjacent tip portion 10^{aa} or the bar 10. These tip portions 10^{aa} provide a greater surface about which the bar 10 may be pivoted and are adapted to be removed when the amount of space about the end of the pipe being removed limits their use for permitting the puller to be conveniently used to remove pipes and tubes regardless of the amount of space around the tube. In use the end of the bolt 14 to which the ring 13^a is attached will dig into the pipe or tube 11 while being collapsed for permitting the bar to more securely grip the end thereof.

According to the modification of the invention shown in Figs. 7 and 8 the construction of the collapser and puller is similar to that previously described except that the ring 13^a is securely mounted in position between a pair of upwardly extending lugs 18. These lugs 18 extend from the end portions of a pair of semi-circular members 19 which engage about the bar 10 adjacent the upturned end 10^a thereof. These semi-circular portions 19 are secured in position by means of rivets 20.

According to the modification of the invention shown in Figs. 9 and 10 a means is provided for fixedly holding the gripper member in various positions along the end portion 10^a of the bar 10. In this form of the invention the chain 13' is attached to a bolt 14'. This bolt 14' passes through an elongated longitudinally extending slot 21 formed in the end portion 10^a of the bar 10. The bolt 14' is provided with a square head 14^b having a plurality of laterally extending serrations 22 which are adapted to cooperate with similarly extended serrations 23 formed on the adjacent face of the bar 10 on either side of the slot 21 in holding the bolt 14' in position on the bar 10. A nut 15' is threadedly engaged on the bolt 14' and is adapted to urge the bolt 14' into a position into which the serrations 22 and 23 will be engaged with each other for holding the bolt 14' in position.

This form of the invention is also provided with reinforcement struts for reinforcing the end portion 10^a and to compensate for the weakening effect caused therein by forming the same with the slot 21. This means comprises a pair of reinforcement struts 24 each of which is mounted upon one side of the bar 10. Each strut 24 comprises a pair of separate sections 24^a arranged in end alignment. The outer ends of the sections 24^a are securely attached to the side walls of the bar 10 adjacent opposite ends of the slot 21. These ends are secured in position by means of rivets 25. The adjacent ends of the sections 24^a are provided with threads extended in opposite directions, and a turn buckle 26 is threadedly engaged on the ends of the sections 24^a for connecting these sections together and for permitting the tension on the struts 24 to be increased when desired for reinforcing the bar 10. In other respects this form of the invention is similar to the previous form.

According to the modification of the invention shown in Figs. 11 and 12 the gripper member takes the form of a strap 27 which is adapted to encircle the end of the pipe or tube 11 and which has its free ends 27^a directed upwards and spaced from each other to receive the end portion 10^a of the bar 10 as shown in Fig. 12. The ends 27^a of the strap 27 are provided with a plurality of vertically aligned openings 28 and the end portion 10^a of the bar 10 is provided with a plurality of openings 29. A bolt 30 is adapted to be passed through an aligned set of the openings 28 and 29 for pivotally mounting the bar on the strap 27 and for causing the strap 27 to be securely engaged about the end of the pipe or tube 11. In other respects this form of the invention is similar to the previous forms.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An exhaust pipe and boiler tube collapser and puller, comprising a bar adapted to be positioned in a substantially horizontal position and having an upwardly curved front end portion, and a gripper member for encircling a pipe or tube and mounted on said curved front end portion, said gripper member comprising a chain, and means for fixedly holding said chain in various positions along the end portion of said bar, said means comprising a bolt attached to the end of said chain and passing through an elongated longitudinally extended slot formed in said bar and means for holding said bolt in various fixed positions along the length of said slot.

2. An exhaust pipe and boiler tube collapser and puller, comprising a bar adapted to be positioned in a substantially horizontal position and having an upwardly curved front end portion, and a gripper member for encircling a pipe or tube and mounted on said curved front end portion, said gripper member comprising a chain, and means for fixedly holding said chain in various positions along the end portion of said bar, said means comprising a bolt attached to the end of said chain and passing through an elongated longitudinally extended slot formed in said bar and means for holding said bolt in various fixed

positions along the length of said slot, and struts for reinforcing the end portion of said bar in the vicinity of said slot.

3. An exhaust pipe and boiler tube collapser and puller, comprising a bar adapted to be positioned in a substantially horizontal position and having an upwardly curved front end portion, and a gripper member for encircling a pipe or tube and mounted on said curved front end portion, and removable tip portions mounted on said bar for shortening the length of said front end portion to permit said bar to be used for removing pipes and tubes where the space about the end of said pipe or tube is limited.

4. A device of the class described, comprising a bar having an upwardly curved front end portion, a bolt extended through an elongated slot formed in said bar in the vicinity of said upwardly curved front end portion, a length of chain having one end secured to said bolt forming a flexible gripping member for encircling the end of a length of pipe or tube, and means for securing said bolt in various adjusted positions along the length of said slot.

5. A device of the class described, comprising a bar having an upwardly curved front end portion, a bolt extended through an elongated slot formed in said bar in the vicinity of said upwardly curved front end portion, a length of chain having one end secured to said bolt form-

ing a flexible gripping member for encircling the end of a length of pipe or tube, and means for securing said bolt in various adjusted positions along the length of said slot, comprising a nut 5 threadedly engaged upon the end of said bolt and engageable against an adjacent face of said bar, and means for preventing said bolt from slipping along the length of said slot when said nut is tightly engaged into position.

10 6. A device of the class described, comprising a bar having an upwardly curved front end portion, a bolt extended through an elongated slot formed in said bar in the vicinity of said upwardly curved front end portion, a length of chain having one end secured to said bolt forming a flexible gripping member for encircling the end of a length of pipe or tube, and means for securing said bolt in various adjusted positions along the length of said slot, comprising a nut threadedly engaged 15 upon the end of said bolt and engageable against an adjacent face of said bar, and means for preventing said bolt from slipping along the length of said slot when said nut is tightly engaged into position, comprising serrations formed on the inside face of the head of said bolt and engageable with complementary serrations formed on the adjacent face of said bar on either side of said slot.

OTTO KOURA.
